CAN OPENER

Don J. Defano, River Grove, and Robert I. Kallman, Geneva, Ill., assignors to Cory Corporation, Chicago, Ill., a corporation of Delaware

Filed Mar. 20, 1961, Ser. No. 64,419

Term of patent 7 years

(Cl. D22—2)

FIG. 1 is a perspective view of a can opener embodying the invention, looking from the right front thereof; FIG. 2 is a top plan view thereof;

FIG. 3 is a right side elevation thereof; and FIG. 4 is a front elevation thereof.

The left side elevation is a substantial mirror image of the right side elevation and the rear and bottom of the can opener are substantially plain and unornamented.

We claim:

The ornamental design for a can opener, as shown and described.
